(57) **CLAIM**

The ornamental design for the decorated panel assembly for a ball, as shown and described.

DESCRIPTION

FIG. 1 is a plan view of the first shaped panel element, shown separate from the assembly for clarity;

FIG. 2 is a plan view of the second shaped panel element, shown separate from the assembly for clarity;

FIG. 3 is a plan view of the third shaped panel element, shown separate from the assembly for clarity;

FIG. 4 is a front view of the assembly;

FIG. 5 is a perspective view thereof;

FIG. 6 is a reduced scale top view thereof;

FIG. 7 is a reduced scale rear view thereof;

FIG. 8 is a reduced scale bottom view thereof;

FIG. 9 is a reduced scale right side view thereof; and,

FIG. 10 is a reduced scale left side view thereof.

The assembly incorporates six of the panel element shown in FIG. 1, four of the panel element shown in FIG. 2, and four of the panel element shown in FIG. 3. The assembly shown in FIGS. 4-10 is spherical with contour lines being omitted to avoid interference with the surface pattern.
